F. W. MILLAY

REMODELED LAST

Filed April 16, 1923

Patented Sept. 15, 1925.

1,553,458

UNITED STATES PATENT OFFICE.

FREDERICK W. MILLAY, OF HAVERHILL, MASSACHUSETTS.

REMODELED LAST.

Application filed April 16, 1923. Serial No. 632,367.

To all whom it may concern:

Be it known that I, FREDERICK W. MILLAY, a citizen of the United States of America, and a resident of Haverhill, in the county of Essex and State of Massachusetts, have invented certain new and useful Improvements in Remodeled Lasts, of which the following is a specification.

This invention relates to lasts and the method of remodeling the same, the object of the present invention being to provide a means whereby a last built for a very high heel may be reshaped to accommodate it to a low heel.

10 The invention consists in taking a last which was made for a high heel, removing a part of the bottom of the forepart, replacing the removed part with a block the bottom of which extends considerably below the

20 plane of former bottom, and then reshaping the forepart of the last and the block secured therein.

The invention further consists of a last reshaped by said method.

25 The invention further consists in certain novel features of construction and arrangement of parts which will be understood readily by reference to the description of the drawings and to the claims to be herein-
30 after given.

For the purpose of illustrating the invention, one preferred form thereof is shown in the drawings, this form having been found to give satisfactory and reliable results, although it is to be understood that the various instrumentalities of which the invention consists can be variously arranged and organized, and that the invention is not limited to the precise arrangement and organization of the instrumentalities as herein shown and described, except as required by the scope of the appended claims.

Of the drawings:

45 Figure 1 represents an elevation of an old last adapted for use in the manufacture of a shoe designed to have a very high heel, and showing the saw cuts made therein for the purpose of removing a portion of the fore part, and indicating in dotted lines the

toe block to be secured thereto, to replace 50 said removed part.

Figure 2 represents the same last with the attached toe part remodeled to make a last adapted for use in the manufacture of a shoe 55 designed to have a low heel.

Figure 3 represents a plan of the bottom of the remodeled last, and

Figure 4 represents a plan of the top of the last with the block removed.

Similar characters indicate like parts 60 throughout the several figures of the drawings.

In the drawings, 10 is the body portion of a last provided with the block 11 which is 65 adapted to be secured in place by the usual fixed pin 12 and locking pin 13. The last is provided with the usual thimble and heel plate 15.

This last 10 as shown in Fig. 1 is intended for use in the manufacture of a shoe with 70 a very high heel. When the style changes and low heels are in vogue, the last is useless and can no longer be used in the manufacture of shoes. To make it possible to utilize the body of the last in the manufacture of shoes is one of the principal aims 75 of the present invention.

In order to accomplish this result, a saw cut 16 is made in the forepart of the last from the toe toward the rear to the ball 80 portion of the last, this cut being substantially parallel with the bottom of the forepart. Another saw cut 17 is made in the forepart at the ball portion thereof from the bottom upwardly, meeting the saw cut 16, 85 said saw cut 17 extending from one side of the forepart to its opposite side. This saw cut 17 is made somewhat inclined, thereby forming an undercut wall.

The saw cut 17 is also made diagonally of 90 the bottom of the last as indicated in Fig. 3 of the drawings. When the saw cuts 16 and 17 have been made in the last, the portion 18 may be removed, thereby leaving a depression in the bottom of the forepart with an undercut rear wall 17.

Having removed this portion 18, a block 19 is substituted therefor, the upper flat face

thereof bearing against the flat face 16 of the forepart, while the rear end of the block 19 fits against the undercut wall 17 of the forepart.

5. This block 19 is much thicker at the toe end of the last than at the rear, as indicated clearly in dotted lines in Fig. 1.

The block is secured to the face 16 and undercut wall 17 by glue or other adhesive, 10 and is also secured to the body portion 10 of the last by means of the screws 20, 21, extending in opposite directions.

When this block 19 has thus been secured in position, the last 10 with the block 19 secured thereto is placed in a turning lathe and turned down to form a new toe portion 22, the toe end of which is considerably lower than the original toe before the portion 18 has been cut away.

20. The outer surface of the new toe 22 is made to conform to the outer surface of the body portion 10 of the last. When this has been accomplished, the adjacent edges of the new toe portion 22 and the body portion 10 are united together by metal plates 23, having shoulders formed thereon, these plates 23 being driven into the wood so as to lock the two parts together and prevent any separation thereof. The new toe portion 22 is 25 made from wood, the grain of which extends toward the toe end of the part 22, thereby making the last much stronger than was the toe portion of the original last.

It is obvious from an inspection of Fig. 2 30 that by this method a last such as is shown in Fig. 1 intended for use in the manufacture of shoes with high heels can be quickly transformed into a last such as is shown in Fig. 2, on which low-heeled shoes may be 35 manufactured.

This is a great advance in the art as heretofore the old lasts could not be utilized and were thrown away or used for kindling. By 40 the present invention, the body portion of the last may be saved and a new and stronger last may be remodeled therefrom at a great saving to the shoe manufacturer.

It is believed that the operation and many 45 advantages of the invention will be understood readily without further description.

Having thus described my invention, I claim:

1. A remodeled last having the entire bottom portion thereof removed from the toe 50 to a point adjacent the ball of the last, leaving at the top of the fore part an extension projecting forwardly to a point near the toe; and a toe piece permanently secured to the under face of said extension with its opposite sides extending to said ball portion and its outer surface conforming to the outer 55 surface of the body of the last.

2. A remodeled last having the entire bottom portion thereof removed from the toe 60 to a point adjacent the ball of the last, leav-

ing at the top of the fore part an extension projecting forwardly to a point near the toe, at the rear end of which is a straight wall extending downwardly therefrom transversely of the fore part; and a toe piece permanently secured to the under face of said extension and to said rear wall with its opposite sides extending to said ball portion and its outer surface conforming to the outer surface of the body of the last. 70

3. A remodeled last having the entire bottom portion thereof removed from the toe to a point adjacent the ball of the last, leaving at the top of the fore part an extension projecting forwardly to a point near the toe, 80 at the rear end of which is a straight undercut wall extending downwardly therefrom transversely of the fore part; and a toe piece permanently secured to the under face of said extension and to said rear wall with its opposite sides extending to said ball portion and its outer surface conforming to the outer 85 surface of the body of the last.

4. A remodeled last having the entire bottom portion thereof removed from the toe 90 to a point adjacent the ball of the last, leaving at the top of the fore part an extension, projecting forwardly to a point near the toe, at the rear end of which is a straight undercut wall extending diagonally in a straight 95 line from side to side of the last; and a toe piece permanently secured to the under face of said extension and said rear wall with its opposite sides extending to said ball portion and its outer surface conforming to the outer 100 surface of the body of the last.

5. A remodeled last having a part cut away from its bottom from the toe to the ball portion thereof leaving a forward extension with a flat bottom surface extending 105 from side to side of the last and nearly to the toe; and a toe piece permanently secured to said flat bottom surface with its outer surface conforming to the outer surface of the body of the last and its toe considerably below the original toe. 110

6. A remodeled last having the entire bottom portion thereof removed from the toe to a point adjacent the ball of the last leaving at the top of the fore part an extension projecting forwardly to a point near the toe, said extension having a flat bottom extending from one side of the fore part to the opposite side thereof; a toe piece fitted to said flat bottom with its opposite sides extending to said ball portion and its outer surface conforming to the outer surface of the body of the last; and means extending through said toe piece into the fore part to permanently secure said toe piece and fore part together. 120

7. A remodeled last having the entire bottom portion thereof removed from the toe to a point adjacent the ball of the last leaving at the top of the fore part an extension 125

- projecting forwardly to a point near the toe, said extension having a flat bottom extending from one side of the fore part to the opposite side thereof with a straight under-
5 cut wall extending from the rear of said bottom face to the bottom of the last; a toe piece fitted to said flat bottom and under-cut wall with its opposite sides extending to
- 10 said ball portion and its outer surface conforming to the outer surface of the body of the last; and means extending through said toe piece into the fore part to permanently secure said toe piece and fore part together.

Signed by me at 746 Old South Bldg., Boston, Mass., this 4th day of April, 1923.

FREDERICK W. MILLAY.
